PHOTO-ELECTRIC TUBE

Heinrich H. Geffcken and Hans R. Richter, Leipzig, Germany

Application December 6, 1928. Serial No. 324,107

3 Claims. (Cl. 250—27.5)

Our invention relates to photo-electric tubes of the kind comprising a sealed bulb which may be of glass, quartz or other suitable material, enclosing a film electrode of light sensitive material (such as potassium, sodium or the like) and containing a second electrode which collects the electrons emitted by the film electrode when the latter is subjected to the influence of light.

In manufacturing such photo-electric tubes in the usual manner, the vaporized material is fed into the tube, and, by cooling certain portions of the tube and simultaneously heating other portions thereof, said material is precipitated on the cooled portion, forming a conducting and light sensitive film. This manner of manufacturing photo-electric tubes can only be performed by skilled experts. The tube is very fragile and bursts easily during this process which requires heating of certain parts and simultaneous cooling of other parts.

Our invention relates to photo-electric tubes, which do not require expert work and which may be manufactured easily without any danger of bursting. The essential feature of our novel photo-electric tube consists in the application of the light sensitive film material to a recessed portion in the wall of the tube.

Our invention will best be understood by detailed description with reference to the accompanying single sheet of drawing.

Figure 1 represents a diagrammatic view of a photo-electric tube, in the state of manufacture;

Figure 2 represents a similar photo-electric tube, the anode electrode of which has a particular shape; and

Figures 3 and 4 represent special embodiments of our invention.

Referring now to Figure 1, a recess 2 is provided in the tube bulb 1 rising centrally therein as shown. Numeral 3 designates the anode electrode. The wire 4 serves as a terminal for the reception of current of the cathodic light sensitive film. During manufacture, the tube 1 is connected with the storage bulb 5 which contains the light sensitive material (e. g., potassium, sodium or the like). The recess portion 2 is closed exteriorly by means of the stopper 6 which supports the tubes 7 and 8. The film of light sensitive material in the tube is produced as follows:

The tube is exteriorly heated and the vaporized photo-electric material is driven from the storage bulb 5 into the tube 1. A current of cold air is simultaneously blown through tube 8 into the interior of the recess portion 2. Conse-

quently, the vaporized photo-electric material precipitates only upon the surface of the inner walls describing the recess 2 and forms there a film 9. In the accompanying drawing this film has been indicated by a heavy line upon the recess portion 2.

In order to line the light sensitive film by a conductive layer, the recess 2 may be coated by a layer of silver or the like before the tube is exhausted. The film of light sensitive material is finally formed by passing a glow discharge in hydrogen. The hydrogen is afterward displaced and suitably replaced by argon, helium or other inert gas.

It is well known, that photo-electric tubes are especially sensitive when the distance between the photo-electric film and the anode member is uniform at all points, providing a nearly homogeneous electric field between the anode electrode and the light sensitive film. This principle can be fully utilized in the present invention due to the general provision of a recess portion, and the sensitiveness of our new photo-electric tube may be increased by surrounding the recess 2 by a suitably shaped anode electrode placed in proper distance relative to the photo-electric film. Figure 2 represents a photo-electric tube of this type. A bag-like net or screen 10 connected to the anode wire 31 is arranged closely to the interior surface of the tube 11, surrounding the light sensitive film 19 applied to the inner wall of the recess in suitable uniform distance at all points.

Instead of using a net or screen 10, the interior surface of the bulb 11 may be coated with a film of silver or the like, and this film may be connected to the anode wire 31 and utilized as anode. In order to avoid undesirable loss of light, this anode film must be extremely transparent. It might be desirable in certain cases to use films of a greater thickness and to divide such film by the use of a scraper device automatically into adjoining sections or into a coiled line, thus providing between the sections smooth, transparent portions.

The scraper devices which may be used for this purpose are well known, for example from the process of manufacturing Rowland grids, and their description is therefore omitted.

In Figure 5 we have shown a portion of the tube to illustrate the application of a metallic film to the walls of the bulb, which may be used for the purpose of an anode in place of the bag-like net as explained above. Like numerals c have been applied in this figure to designate parts already shown and discussed in connection with

Figure 2. The metallic film taking the place of net 10 in Figure 2 is designated in Figure 5 by reference numeral 10'.

Figure 3 represents another embodiment of our invention, showing a case in which the light sensitive film has a spherical shape and surface. Such photo-electric tubes are especially adapted for measuring the total lighting of a point.

Figure 4 represents another embodiment of our invention, showing a photo-electric tube in which the light sensitive film has a cross section of ring formation. Photo-electric tubes of this kind are particularly adapted for the use in connection with the radio transmission of opaque pictures.

In view of the detailed description furnished in connection with Figures 1 and 2, it is believed that the two embodiments shown in Figures 3 and 4 can be readily understood without additional detailed description.

It is understood that various changes and modifications may be made in the structural details and in the arrangement of parts disclosed in this case without departing from the spirit of the invention, and we desire to have it under-

stood, therefore, that what we regard as our invention and what we claim as new is specifically pointed out in the claims which follow:

What is claimed is:—

1. A photo-electric tube, having a sealed elongated envelope provided with a longitudinal recess, a light sensitive cathode film applied to the surface of said recess within said envelope, and a metallic net applied to the inner surface of said envelope opposite said recess. 80

2. A photo-electric tube, having a sealed envelope, a recess in said envelope extending therein, a light sensitive cathode film applied only to the surface of said recess within said envelope, and a metallic anode net applied to the inner surface of said envelope opposite said recess carrying said cathode film. 85

3. A photoelectric tube having a sealed elongated envelope provided with a recess, a light sensitive cathode film applied to the surface of said recess within said envelope, and a transparent anode film applied to the inner surface of said envelope opposite said recess. 90
